UNITED STATES PATENT OFFICE.

ANTONIO VILLALBA DE LA CORTE, OF SAN LUIS POTOSI, MEXICO.

PROCESS OF EXTRACTING RUBBER AND THE LIKE FROM WOOD.

No. 814,675.

Specification of Letters Patent.

Patented March 13, 1906.

Application filed August 31, 1905. Serial No. 276,543.

To all whom it may concern:

Be it known that I, ANTONIO VILLALBA DE LA CORTE, a subject of the King of Spain, and a resident of San Luis Potosi, in the State of San Luis Potosi, Mexico, (whose post-office address is 5^a Calle de Fuente No. 5,) have invented certain new and useful Improvements in Processes of Extracting Rubber and the Like from Wood, of which the following is a specification.

My invention relates to a process for extracting from certain woods the contained rubber or caoutchouc-like substances.

The object of my invention is to extract these substances from the wood by dry means, utilizing pressure and heat to accomplish the end.

For this purpose my invention consists, essentially, in subjecting the wood to a series of 20 successively finer grindings, and during the final stages of the process subjecting the wood to the influence of both pressure and heat, whereby the extracted rubber is caused to agglomerate.

25 The nature of my invention will be best understood in connection with the accompanying drawings, representing one form of apparatus for carrying out my process, in which—

Figure 1 is an end view of the apparatus.

30 Fig. 2 is a front view, partly in section, taken in the direction of the arrow, Fig. 1.

Similar letters and numerals of reference designate corresponding parts throughout both views.

35 In carrying out my process I take, for example, the twigs and branches of a shrub, such as that known as "guayule," which contains considerable rubber, and break them up into suitable lengths, preferably 40 about one inch. These broken twigs or branches are then fed into a suitable apparatus in which they are subjected to repeated grindings under pressure, the material being ground to such a degree that the rubber is 45 mechanically separated therefrom. The separation is assisted during the final stages by heating the material to slightly soften the rubber, and thereby aid its agglomeration.

50 In the form of apparatus shown the broken twigs or branches pass successively through cylinders A, B, C, and D, mounted upon the frame E, being fed into the hopper 1 and then forced through the cylinders by means of screw conveyers 2, 3, 4, and 5, centrally disposed with respect to the cylinders. These 55 conveyers feed the material to grinding ap-

paratus located at the farther end of each cylinder, said apparatus comprising a revolving disk 6 and two stationary disks 7 and 8. These disks are provided with roughened 60 surfaces or with teeth adapted to grind the wood between them. The surfaces vary from a coarse grinding-surface in the first cylinder to a fine grinding-surface in the last, the material thereby being successively 65 ground finer and finer until when it passes out of the last cylinder D the wood is in a very fine state of division. The final cylinder D is provided with a steam-jacket 9, to which steam is supplied at a sufficient pressure to 70 raise the temperature of the ground wood the desired amount, so that the rubber becomes somewhat soft or plastic and readily agglomerates, especially when rubbed between the grinding-plates. By the time the material reaches the cylinder C the rubber begins to separate from the wood, and this separation is completed by the rubbing or 75 grinding action in the next or final cylinder D. On leaving the cylinder D through the 80 outlet 10 the wood has been so thoroughly ground that the agglomerated rubber is in a condition to be readily separated therefrom by hand or the rubber may be cleaned or freed from impurities by suitable washing or cleaning devices. Means are shown in 85 the drawings for adjusting the spaces between the grinding-disks, thereby regulating the resistance, or rather the pressure required for proper extraction. Power to operate the 90 revolving disks and the conveyers is derived from the pulley-wheel 11 and transmitted by a suitable train of gearing to the various shafts. It will thus be seen that by grinding the wood to the proper degree of 95 fineness and subjecting it to considerable pressure in the grinding the rubber or similar products contained therein are extracted therefrom and that the separation is assisted by subjecting such mixture to a temperature 100 sufficient to slightly soften the rubber, causing it to agglomerate more readily.

What I claim as new, and desire to procure by Letters Patent, is—

1. The herein-described process for extracting rubber or caoutchouc-like substances contained in certain woods, said process consisting in subjecting the material to a series of dry grindings under pressure, and to the influence of heat, whereby the rubber is caused 110 to separate mechanically from the wood.

2. The herein-described process for ex-

2
tracting rubber or caoutchouc-like substances contained in certain woods said process consisting in subjecting the material to a series of dry grindings under pressure to mechanically separate the rubber therefrom and in heating said material during the process of grinding or rubbing to aid the agglomeration of the particles of separated rubber.

3. The herein-described process for extracting rubber or caoutchouc-like substances contained in certain woods said process consisting in breaking the wood to be treated into suitable size and subjecting this broken material to repeated dry grindings under pressure and under the influence of heat.

4. The herein-described process for extracting rubber or caoutchouc-like substances contained in certain woods, said process consisting in breaking the wood to be treated into suitable size, subjecting this material to successively finer dry grindings and during the final grinding to pressure and heat. 20

Signed at New York, in the county of New York and State of New York, this 21st day of August, A. D. 1905.

ANTONIO VILLALBA DE LA CORTE.
